ARTICLE CATCH DEVICE FOR OUTFLOW
PASSEGES

Herman Max Lehmann, Seattle, Wash.

Application February 21, 1952, Serial No. 272,793

3 Claims. (Cl. 4—257)

This invention relates to devices designed for use to prevent the clogging of toilet bowls by articles such as wash cloths, heavy paper, "Kleenex," and various other articles or objects which by accident, inadvertence or otherwise are dropped into but which should not be disposed of through the toilet bowl.

More specifically stated, the present invention pertains to devices designed to be applied within the outlet of the bowl to catch and retain such articles for removal so that they will not enter, and possibly clog the bowl outlet or the sewer connections.

It is the principal object of this invention to provide a device for the above-stated purpose that is relatively simple in construction; that can be easily and quickly applied without a plumber's aid; that will in no way interfere with the normal use and operation of the toilet in its intended manner; that will not retain toilet paper as ordinarily used and which will last for an indefinite period.

It is a further object of the present invention to provide devices of the above stated kind, that can be readily applied to any of the standard or present day toilet bowls, and which requires no change or alteration in the bowls or sewer connections in order that they can be applied.

Further objects of the invention reside in the details of construction and combination of parts embodied in the device and in the mode of application and manner of use of the device as will hereinafter be fully described.

In accomplishing the above mentioned and other objects of the present invention, I have provided the improved details of construction, the preferred forms of which are illustrated in the accompanying drawings, wherein—

Fig. 1 is a perspective view of an embodiment of the present invention in one of its preferred forms of construction.

Fig. 2 is a perspective view of a device in accordance with this invention, of an alternative form.

Fig. 3 is a view showing a typical toilet bowl in cross section, and illustrating the place and manner of applying the device of this invention to the bowl outlet.

Fig. 4 is a view showing an alternative form of catch hook for use with the present device.

The present invention is intended to be used to prevent the trouble, and expense that is caused by persons, usually children, carelessly or inadvertently throwing such articles as wash cloths, newspaper, heavy paper that will not readily disintegrate when wet, and various other articles, in the toilet bowl, it being well known that such articles may and do frequently clog the bowl outlet or clog the sewer connections. The invention anticipates that the device shall be easy to apply; will not in any way interfere with normal use of the toilet; which will catch and retain any article which is apt to cause trouble in the bowl or disposal connections of the toilet.

The utility of the present device is enhanced by reason of the fact that practically all present day toilet bowls have outflow channels of substantially the same diameter, and all flushing toilets operating in substantially the same manner. While various bowls differ somewhat in design, they do not differ in any material respect in those parts with which the present device is applied. Therefore, it is to be understood that in the present illustration of a toilet bowl, this is intended to be representative of any one of those which are now in general use.

10 broad claims to the device as herein described.

2

Referring more in detail to the drawings—
In Fig. 3, I have shown a typical toilet closet of flushing or washdown type, designated in its entirety by reference numeral 10. It comprises the bowl portion 11 with 15 upwardly and rearwardly directed outflow channel 12 leading from the bottom thereof. This channel leads upwardly to sufficient height above the entrance thereto from the bowl as to form a water seal. The channel then turns downwardly and connects to the sewer pipe 10 in the usual way.

The device of this application is designed for application or removal through the top opening of the bowl, to the inlet portion of the outflow channel 12. In its present preferred form of construction the device comprises an expandable ring 20 adapted to be received in the channel 12, and to be held where placed by reason of its tendency to expand. Attached to the band, and extending upwardly and rearwardly into the channel 12, is a hook 21 with back turned and sharpened point 21'.

20 In its present preferred construction, the ring 20 is made from a single flat strip of spring steel. This strip is sprung into circular form, with its opposite end portions extended in opposite directions and flatly overlapped one with the other. At each of the ends of the strip, flat loops 24 are fixed thereto, and each of these 25 slidably receive the band therethrough. In this way the circular form is retained while the band is permitted to be contracted. The resiliency of the strip causes it to be expanded and to fit itself tightly in any channel up to a maximum; this pressure being sufficient to hold the device functionally in place. In lieu of employing a spring steel strip to form the ring, it has been found practical also, to use plastic strips, or metal other than steel. Furthermore, while it is desirable, as considered from the standpoint of quick and easy application of the device 30 to employ the expandable ring, it is also practical to employ a ring of fixed diameter, with friction knobs or bands applied thereto for retaining it properly in the outflow channel 12 by reason of its closeness of fit.

35 The hook 21 employed as a part of the device has a shank portion 21x extended in an upward curve from the bottom of the ring to about the center of the channel, and there formed with the sharpened hook. Also, it is desirable that the shank be flattened and sharpened along its inside edge, as seen at 28 in Fig. 1, leading up to the hook in order to cause cutting and an easier passage of the usually used toilet paper. The attached 40 end of the hook shank preferably is flattened in such manner as to avoid to the greatest possible extent, the catching of any material on it.

45 A device presently in use has a ring that is adjustable to a maximum of 3 1/4" in diameter, and the hook shank is about 4" long.

50 In Fig. 2, I have shown an alternative form of device wherein the ring and hook are both formed from a single and continuous strip of spring wire. This wire is formed at one end with a hook shank 30 and back turned point 30', corresponding to the hook of the first described device, and the remainder of the wire is formed into a helical, contractible and expandable coil 31 of several turns. This coil can be manually diametrically retracted and when retracted can be placed in the bowl channel 12. Upon release, it automatically expands to the full diameter of the channel and holds itself in place by the expanding pressure against the channel walls.

55 While I have shown the present device as having but one catch hook, more may be used if so desired. However, when more than one is used, there is a greater chance that the passage may become clogged by toilet paper.

60 In Fig. 4, I have illustrated use of a two pointed hook. In this device the hook shank 21x is bifurcated and each of its two branches has a back turned, sharpened point. These points should be about one inch 65 apart for best results.

65 Devices of the kind herein shown will operate to catch and retain such articles as wash cloths, heavy paper, rags, string and other articles which are apt to cause sewer or sewer connection clogging. Such devices can be easily and readily applied by a layman, and just as 70 easily removed if such is desired. To prevent rust of metal

parts, the device would be rubber or plastic coated or otherwise treated. Furthermore, the hooks might be made and applied in various ways other than shown without departing from the spirit of the invention.

Objects, such as wash cloths, heavy paper, etc., when caught by the hook do not ordinarily remain in the channel, but float back into the bowl for easy removal, after the flushing operation has stopped.

It has been found that by so forming the hook shank that a short portion thereof, which is immediately adjacent the ring, will extend along and bear against the channel wall, there will be no possibility of the device turning sideways and becoming displaced from position.

While I have shown the present device as applied to a toilet bowl, it is anticipated that such devices be made in various sizes, as may be required, to adapt them for use in drains, outlets, or catch traps, other than toilets, wherever there is a possibility of clogging by rags, paper, etc.

Having thus described my invention, what I claim as new therein, and desire to secure by Letters Patent, is:

1. A device of the character described comprising a resilient member of ring-like form adapted to be compressed for application within a tubular outflow passage and by reason of its resiliency to expand after application thereto and upon release, to effect its functional securing in the passage by its expanding pressure against the passage walls, and an article catch element comprising

ing a shank fixed at one end to the resilient member and extending away from the resilient member and toward the center thereof, the free end of the catch element being reversely bent upon the shank with the ultimate end being sharpened to a hook-like structure, the hook-like structure extending into the direction of flow through the passage so as to engage and prevent the outflow of passage obstructing material.

2. A device as in claim 1 wherein the catch element member is bifurcated at its free end and includes a plurality of hook-like structures.

3. A device as in claim 1 wherein the device is formed from a single and continuous strip of spring wire.
